In Germany November 29, 1935

5 Claims. (Cl. 121—38)

This invention relates to presses and is illustrated as embodied in a press particularly adapted to smooth-plating and embossing operations upon hides, skins and leather. It is to be understood, however, that the invention and various important features thereof may have other applications and uses.

The present invention is an improvement upon the press disclosed in United States Letters Patent No. 1,932,556, granted October 31, 1933, upon application of P. V. J. Merenda.

It is an object of this invention to facilitate and expedite the return of the platen and platen-operating pistons toward their lower or initial positions in a press of the type disclosed in the said patent.

To these ends, and in accordance with an important feature of the invention, the movable platen of a press is arranged to be operated by a large piston and by a smaller piston which not only moves the large piston during upward movement of both pistons and controls the application of pressure by the pressure medium to the larger piston, as in the patented construction, but will also provide by its construction for release of pressure below the large piston and also the actual discharge of the pressure medium from the chamber below the large piston, thus facilitating and expediting the return of the large piston and of the platen carried thereby to their initial or lower positions. For this purpose the small piston is provided with a bore or other passageway which extends in line with its axis the full length of the small piston, the result being that the pressure medium below the large piston may escape through the passageway thus afforded in the small piston, this operation taking place promptly upon release of pressure in the cylinder back of the small piston through the opening of a valve under control of the operator.

These and other features of construction and novel combinations of parts will now be pointed out in detail in the specification and then pointed out more particularly in the appended claims.

45 In the drawing,

Fig. 1 is a front view, partly in section, of the essential elements of a press illustrating one embodiment of the invention; and

Fig. 2 is a sectional view illustrating another 50 species of the invention.

In the illustrated press, which is specially designed for smooth-plating and embossing operations upon hides, skins and leather, there is provided a cylinder 4 having a chamber 5 for the reception of a relatively large piston 6 having a con-

cave upper surface for the reception of a convexly rounded portion of a platen member 8 having formed integrally therewith a platen 10 adapted to co-operate with an upper stationary platen 12 carried by a head 14. Below the large cylinder 4 is a smaller cylinder 16 having a cylinder chamber 18 which communicates with the chamber 5 of the cylinder 4. Movable in the cylinder 16 is a smaller piston 20 having extending completely therethrough a bore 24, the upper portion of the bore being restricted in size to form a vent 26. As shown, the upper end of the piston 20 has a surface portion around the vent 26 which is machined flat and contacts a similar flat surface on the lower end of the large piston 6. Hence the vent 26 is normally closed while the press is at rest and during all of the time that the pistons 6 and 20 are rising toward pressure applying position and also during all the time that pressure is being applied to a given piece of work. In addition, the upper end of the piston 20 has an annular surface 27 against which pressure may be exerted in a downward direction by the pressure medium to move this piston downwardly when pressure is removed in the chamber 18 to cause opening of the press. Extending laterally from the bore 24 of the small piston 20 are ports 28, these ports serving a purpose which will later be explained herein.

Opening into the chamber 5 of the cylinder 4 is a pipe 30 leading to a valve box 32 in which is a valve 34 normally held in closed position by a spring 36, the latter being engaged with a disk member 38 rigidly secured to stem 40 which carries the valve 34. As shown, this stem 40 of the valve 34 extends through the valve box 32 a substantial distance in an upward direction so that said valve may be controlled by a lever 42 pivoted at 44 to the upper end of a link 46 in an arrangement wherein the free end of the lever 42 is pivotally received within a socket 48 carried by a bracket 50 secured to the upper end of the large piston 6. It will be readily understood that as the large piston descends from its uppermost position, shown in Fig. 1, the lever 42 is operated to cause depression of the stem 40 and its valve 34 whereby the pressure medium (e. g. water or oil) within the cylinder chamber 5 may readily escape through the pipe 30 and through a second pipe 52 to a reservoir (not shown).

Opening into the chamber 18 of the lower cylinder 16 is a pipe 54 through which the pressure medium may be introduced into the cylinder 16 or removed therefrom.

In that species of the invention shown in Fig. 2, a small piston 60 has a chamber 62 somewhat 55

larger than the corresponding chamber 24 of the piston 20. However, the chamber 62 has a vent 64 at its upper end similar in all respects to the vent 26 leading from the chamber 24 in the piston 20. Moreover, piston 60 has an annular surface 65 for the same purpose as the corresponding surface 27 on piston 20 (Fig. 1). The lower end of the piston 60, in Fig. 2, is screw threaded interiorly to receive a closure member 66 which is provided with a number of ports 68. As shown the closure member 66 has also an opening central therethrough for the slidable reception of a rod 70 having an enlarged head 72 which operates as a stop to limit upward movement of the small piston 60. Conveniently the rod 70 is extended through the lower end wall 74 of the small cylinder 16 and is provided with a nut 76 adjustably screwed thereon and operative to hold the rod 70 at a predetermined position within the cylinder 16.

For a more detailed description of this press, and particularly of the controller member and valves which enable the operator to control the press, reference should be had to said Patent No. 1,932,556.

In the operation of the press shown in Fig. 1, the pressure medium (usually oil or water) is introduced into the cylinder 16 through the pipe 54 under pressure by a pump (not shown) upon proper manipulation of a control member for a valve, also not shown. While the press was at rest, the lower end of the piston 20 was maintained above the level of the opening of the pipe 54 by a spring device indicated at 80, the arrangement being such that the large piston 6 rested upon the upper end of the small piston 20. Hence, when the pressure medium is introduced under pressure into the chamber 18, the small piston is forced upwardly carrying with it the large piston 6, there being no escape of the pressure medium through the vent 26 which is closed through the contacting surfaces on the pistons 6 and 20, as already described. During upward movement of the pistons 20 and 6, the pressure medium is drawn into the chamber 5 of the large cylinder 4 from a reservoir (not shown) through the pipes 38 and 52, since the valve 34 is open during practically all of the upward movement of the large piston 6. At the beginning of the pressure applying operation upon a piece of work between the platens 10 and 12, the ports 28 in the piston 20 come into place above the floor of the chamber 5 so that the pressure, which up to this time has been confined to the chamber 18 of the small cylinder 16, is now transmitted through the ports 28 to the pressure medium in the chamber 5 of the large cylinder 4, thus causing the application of heavy pressure upon the lower platen 10 due to the very much increased area, that of the lower surface of the large piston 6, now subjected to pressure by the pressure medium. It will be understood that the instant that pressure was applied through the ports 28 to the pressure medium in the chamber 5, the valve 34 was closed. Pressure is thus maintained between the platens 10 and 12 for any desired length of time. When the operator decides that the work piece has received proper treatment, a controller member (not shown) is operated to open a release valve in a pipe leading from the chamber 18. This results in an instantaneous drop in the pressure in the chamber 18 with the result that both pistons 6 and 20 descend until ports 28 are closed. The weight of the piston 6 and superposed platen 10 produces pressure in the medium in the

chamber 5 which, acting on the surface 21, forces the small piston 20 downwardly. It follows that to the vent 26 is opened upon the instant that the piston 20 starts to descend relatively to the piston 6. Hence the pressure medium may escape through the vent 26 and through the bore 24 of the small piston 20. In this way and by the special construction of the small piston, the return of the large piston toward its lower position is substantially expedited. Normally the piston 20 continues to descend faster than the large piston 6, it being understood in this connection that, unlike piston 6, there is no packing about the piston 20, the latter having a snug running fit in the cylinder 16. However, piston 6 also descends and soon causes opening of the valve at 34 through the operation of the lever 42, thus adding another exit for the pressure medium in the chamber 5.

Since the ports 28 in the piston 20 occupy a predetermined position in the length of the said piston, it follows that the range of thicknesses of the pieces of work to be treated must be known and adhered to, it being obvious that a piece of work thicker than this said range of thicknesses would prevent the ports 28 reaching operative position and hence the desired heavy pressure could not be applied within any reasonable time through the pressure medium in the chamber 5. For this reason there has been provided another construction of the small piston, namely, that shown in Fig. 2, wherein the ports 64 and 68 become effective to transmit pressure to the pressure medium in the large chamber 5 when the small piston 60 is held from moving upwardly beyond a certain predetermined point by the head 72 of the rod 70. In this case the pressure medium passes through the ports 68 through the bore 62 and vent 64 to the chamber 5 whereby heavy pressure is applied to the piston 6, it being possible to make very readily any desired adjustment of the rod 70, by proper manipulation of the nut 76, and hence of the position of the small piston at which pressure will be applied to the large piston 6. In fact, the desired adjustment may be made with the press in operation. It will be understood that small piston 60 is stopped by head 72 of rod 70 just at the instant the piece of work on the platen 10 contacts the platen 12 and before application of pressure to the work piece. Hence the pressure medium may be forced through the vent 64 whereby pressure is applied in the chamber 5 to large piston 6. Otherwise, the press embodying the piston 60 operates in a manner similar to the press containing the piston 20. Upon releasing pressure in the chamber 18 (Fig. 2) to terminate a pressure applying operation, the pressure in the chamber 5 instantly drops substantially to that of chamber 18, since the vent 64 is uncovered when the piston 60 and platen 10 are in their uppermost pressure applying positions. Hence the pressure medium in chamber 5 escapes through the passageway in the small piston 60 to the chamber 18. Since some portion of the pressure medium flows over the topmost surface of the piston 60 and escapes from the chamber 5 downwardly through vent 64, there is a distinct tendency for the pressure in the medium about the vent 64 to drop, so that pressure on the upper flat surface of the piston 60 is less than it would be were there no vent. Probably there is only small downward pressure on the topmost surface of the piston. Hence, there is an advantage in providing this piston 60 with an annular surface 75

65, away from the vent 64, upon which pressure may be exerted in a downward direction by the pressure medium in the chamber 5, the pressure in the chamber 5 being due to the weight 5 of the piston 6 and superposed platen 10. The piston 60 descends, ahead of the piston 6, by reason of its own weight aided by the pressure on the surface 65. Hence the passageway in the piston 60 serves for the discharge of the pressure medium in chamber 5, (Fig. 2) to insure that the piston 6 may descend promptly to effect opening of a valve, corresponding to valve 34 (Fig. 1), whereby the medium in chamber 5 may be evacuated.

15 Having described my invention, what I claim as new and desire to secure by Letters Patent of the United States is:

1. In a hydraulic press, a movable platen, a cooperating platen, a large piston supporting the 20 movable platen to operate the latter, a cylinder in which the piston is movable, a small cylinder below the large cylinder and communicating therewith, and a small piston in said small cylinder having a bore extending therethrough substantially parallel to its axis, said small piston having further a flat upper end surface to contact a similar flat surface on the lower end of the large piston whereby the upper end of the bore in the small piston is closed while both pistons are in their lowermost position and also during upward movement of the pistons, caused by pressure behind the small piston to effect closing of the platens as a preliminary to the application of heavy pressure to the work piece in the press, 35 and said bore in the small piston serving as a passageway for the escape of the pressure medium from the large cylinder upon release of pressure in the small cylinder.

2. In a hydraulic press, a movable platen, a 40 cooperating platen, a large piston supporting the movable platen to operate the latter, a cylinder in which the piston is movable, a small cylinder below the large cylinder and communicating therewith, and a small piston in the small cylinder having a flat upper end surface to contact with the flat lower end surface of the large piston when the latter is in its lowermost position, said small piston having a bore extending throughout its length and opening flush on the said upper end surface of the small piston whereby the upper end of the bore is closed by the large piston, a pressure medium being applied under pressure to the lower end of the small piston whereby the latter is caused to rise and to lift 45 also the large piston, said small piston having a port opening laterally from its bore and operative at a certain point in the upward movement of the small piston to transmit pressure from the pressure medium in the small cylinder to that in the large cylinder whereby the large piston is moved upwardly under heavy pressure substantially at the end of its upward movement, and said bore in the small piston serving as a passageway for the escape of the pressure medium

from the large cylinder upon release of pressure in the small cylinder.

3. In a hydraulic press, a movable platen, a cooperating platen, a large piston supporting the movable platen to operate the latter, a cylinder 5 in which the piston is movable, a small cylinder below the large cylinder and communicating therewith, a small piston having a flat upper end surface to contact the lower end surface of the large piston and having further a chamber extending throughout the greater part of the length 10 of said small piston with an opening onto the said flat upper end surface of the small piston, said opening being normally closed by said large piston, a rod extending through the lower end 15 wall of the small piston into the chamber thereof and having an enlarged end to serve as a stop to limit the upward movement of the small piston, and the lower end wall of the small piston having a number of ports furnishing permanently 20 open passageways between said small cylinder and the chamber of the small piston whereby the pressure medium is always free to pass in one direction or the other between the small cylinder and the chamber of said small piston, the 25 arrangement being such that the pressure medium passes promptly from the large cylinder through the small piston to the small cylinder upon release of pressure in the small cylinder.

4. In a hydraulic press, a movable platen, a 30 cooperating platen, a large piston to operate the movable platen, a cylinder in which the piston is movable, a small cylinder in line with the large cylinder and communicating therewith, and a small piston movable in said small cylinder and 35 having a passageway therethrough from one end to the other, said small piston having further a flat end surface upon which said passageway opens and adapted to contact a similar flat surface on the adjacent end of the large piston 40 whereby that end of said passageway in the small piston is closed while both pistons are moving together, and said small piston having also an annular surface at the same end as the said flat surface and at one side of the plane of said flat 45 surface.

5. In a hydraulic press, a movable platen, a 50 cooperating platen, a large piston supporting the movable platen to operate the latter, a cylinder in which the piston is movable, a small cylinder below the large cylinder and communicating therewith, and a small piston in said small cylinder having a passageway therethrough from one 55 end to the other, said small piston having further a flat upper end surface to contact a similar flat surface on the lower end of the large piston whereby the upper end of said passageway in the small piston is closed while both pistons are moving upwardly together and while pressure is being applied to a work piece, and said small piston 60 having also an annular beveled-off surface at its upper end below the plane defined by said flat surface at the upper end of the small piston.

PAUL V. J. MERENDA.
